UNITED STATES PATENT OFFICE

GEORGE MCPHEE, OF TORONTO, ONTARIO, CANADA, ASSIGNOR TO WEBB'S BEVERAGES
(CANADA) LIMITED, OF TORONTO, ONTARIO, CANADA

DESIGN FOR A BOTTLE

Application filed September 11, 1931, Serial No. 41,070, and in Canada July 31, 1931. Term of patent 14 years

To all whom it may concern:

Be it known that I, GEORGE MCPHEE, a subject of the King of Great Britain, and resident of the city of Toronto, Province of Ontario, in the Dominion of Canada, have invented a new, original, and ornamental Design for a Bottle, of which the following is a specification, reference being had to the accompanying drawings forming part thereof.

I claim:

The ornamental design for a bottle as shown and described.

GEORGE MCPHEE.
